UNITED STATES PATENT OFFICE.

FRANK L. PINNEY, OF THE UNITED STATES NAVY.

RAZOR-STROP.

No. 910,856.

Specification of Letters Patent.

Patented Jan. 26, 1909.

Application filed April 8, 1908. Serial No. 425,884.

To all whom it may concern:

Be it known that I, FRANK L. PINNEY, lieutenant United States Navy, a citizen of the United States, residing at Annapolis, in the county of Anne Arundel and State of Maryland, have invented certain new and useful Improvements in Razor-Strrops; and I do hereby declare the following to be a full, clear, and exact description of the invention, 10 such as will enable others skilled in the art to which it appertains to make and use the same.

My invention relates to razor strop hangers, and has for its object the production of 15 a hanger which may be readily applied to existing strops, and which will take over a nail, peg, or other projection, as well as bite into a shelf, ledge or other flat surface.

A further object of my invention is to so 20 shape the hanger as will enable one to fold the strop for packing away and to inclose the folds in the hook portion of my hanger, as will more fully appear.

To these ends my invention consists in the 25 novel structure and combination of parts more fully hereinafter disclosed and particularly pointed out in the claims.

Referring to the accompanying drawings forming a part of this specification:—Figure 30 1, is a plan view of one end of a strop with my hanger attached. Fig. 2, an edge view of the same. Fig. 3, a detail sectional view showing one of the jaws of my clip. Fig. 4, a plan view of my hanger detached showing 35 the clip jaws partially open, and Fig. 5, a view similar to Fig. 2, showing how the folds of the strop may be nested in the hook portion of my hanger, and Fig. 6, shows a modification formed by twisting the jaws together.

40 Like numerals refer to like parts in all the views.

1; indicates the strop proper; 2, the usual swivel hook or eye attached to said strop; 45 3, my improved detachable strop hanger. This hanger consists of the two main jaws 4 and 5, which are practically duplicates of each other and pivoted together as at 6.

Each jaw is preferably provided with a rounded portion 7, a flat portion 8, and a 50 hook portion 9. The rounded portion 7, of each jaw is preferably cut away at 10, and so turned up as to almost form a complete ring, as shown.

The cut away half rings thus formed at the 55 extreme ends of each rounded portion 7, when brought together, as shown in Figs. 2

and 4, constitute a clip, which is adapted to embrace and snugly hold the swiveled eye 2 of the strop. The flat portions 8 of the jaws 4 and 5 are slightly bent and fitted into each other, as shown at 11, at those portions through which the rivet 6 passes, in order that there may be friction when the said jaws are swung on their pivot 6, all as best shown in Fig. 2. The effect of this action is to 60 cause the clip members 10 when once locked, to stay locked until they are forcibly separated by swinging the parts upon the pivot 6. Of course, since the hanger is made of wire, the part 6 may be simply a rivet immovably 70 binding the jaws 4 and 5 together, and the clip members 10, may be simply forcibly sprung apart, in order to disengage them from the swivel 2. This may be readily accomplished by forcing the said members 75 apart in a direction perpendicular to the plane in which they lie, and the swivel 2 inserted between the same, in a manner similar to that in which a key is slipped over a key ring.

The upper portions 9 of the jaws 4 and 5 are hook shaped, as shown, and the extreme ends of the same are beveled off to form a sharp point 12, as shown. The hooks formed by the parts 9 are preferably of sufficient dimensions and of the proper size to accommodate 85 the folds of the strop when doubled up for packing away, as best shown in Fig. 5.

In operation it is only necessary to snap 90 my hanger into the swivel 2 of the ordinary razor strop, and to then sling the same over a nail, peg or other projection that may be convenient when stropping the razor. Or if no such projection is convenient, owing to the sharp points 12 with which the hooks 9 95 are provided, I may bite the hanger into a ledge, window sill or other plain surface that may be convenient. The outwardly curved lower portions 7 of the jaws 4 and 5 form a 100 round hole, which renders the hanger capable of being readily placed over a nail or peg, and the tapering triangular space above this hole enables the hanger to be readily wedged against said nail or peg and thereby firmly held. In other words, it will be readily observed that I have at least three ways of firmly securing my razor strop to surfaces or objects that may be handy in a room, and that in addition thereto my hanger serves as a sort of a holder for the strop when folded 110 up for packing away.

The hanger *per se*, as shown in Figs. 4 and

6, may be manufactured separate from the strop and sold as a separate article to be attached to any of the strops now in use.

Of course I do not wish to be limited to the 5 exact details of construction above disclosed, since it is evident that the same may be widely varied without departing from the spirit of my invention.

What I claim is:—

- 10 1. A razor strop hanger, comprising a pair of jaws secured together, and each having a hook member at one end and a clip member at the other end, said hanger being readily attachable to the swivel of the razor strop, 15 and said hook members being disposed in a plane at right angles to the plane of the clip member substantially as described.
- 20 2. A razor strop hanger, comprising a pair of jaws secured together, each jaw having a pointed hook member at one end, an oppositely curved rounded portion 7, and a clip portion 10 at the other end, disposed in a plane at right angles to the hook members, 25 whereby the said jaws form a hanger having a pair of hooks, provided with a hole adapting it to be slipped over a nail like projection, and a clip adapting it to be readily attached to a strop, substantially as described.
- 30 3. A razor strop hanger, comprising a pair of jaws secured together, each jaw provided with oppositely disposed cut away ring like portions 10, forming a clip; oppositely

curved portions 7 forming a hole; converging portions 8 forming a triangular space leading from said hole; and curved portions 9 forming hooks, disposed in a plane at right angles to the plane of the clip, substantially as described. 35

4. A razor strop hanger, comprising a pair of jaws secured together, each jaw provided with oppositely disposed ring like portions forming a clip; oppositely curved rounded portions forming a circular inclosure adapted to receive a nail like projection; flat converging portions forming a triangular space leading from said circular inclosure; said flat portions being bent and fitted against each other; and hook like portions with sharpened points, substantially as described. 40 45

5. A razor strop hanger, comprising a pair of jaws secured together, each jaw provided with oppositely disposed ring like parts forming a clip; oppositely curved rounded portions; and hook like portions disposed in a plane at right angles to the plane of the 55 clip adapted to receive the folds of the strop when doubled up for packing, substantially as described.

In testimony whereof, I affix my signature, in presence of two witnesses.

FRANK L. PINNEY.
